VAPOR ELECTRIC SYSTEM

Joseph H. Cox, Pittsburgh, and Henry C. Myers, Irwin, Pa., assignors to Westinghouse Electric & Manufacturing Company, East Pittsburgh, Pa., a corporation of Pennsylvania

Application August 2, 1940, Serial No. 349,656

3 Claims. (Cl. 175—354)

Our invention relates to a vapor-electric device, and particularly to a control system for a vapor-electric converter of the make-alive type.

In the operation of vapor-electric valves of the make-alive type, it has been found desirable to enclose the anode in a suitable anode shield in order to increase the stability and rating of the device. When using such anode shields, considerable difficulty has been encountered in regularly establishing the main current-carrying arc between the main anode and cathode. We have found that if suitable potential is applied to the anode shield, it serves as an exciting or ionizing device and greatly assists in the pick-up of the main arc in the device.

It is accordingly an object of our invention to provide a control system for periodically applying control or exciting potentials to the anode shields of a make-alive type valve.

It is a further object of our invention to provide a control system for reliably controlling make-alive type valves.

Other objects and advantages of our invention will be apparent from the following detailed description, taken in conjunction with the accompanying drawings, in which:

Figure 1 is a schematic illustration of a vapor-electric converter according to our invention; and

Fig. 2 is a similar figure showing a preferred modification according to our invention.

In the illustrated embodiment of our invention according to Figure 1, an alternating-current circuit 1 is connected to a direct-current circuit 2 by means of a suitable connecting transformer 3. The secondary phase terminals of the connecting transformer 3 are connected to suitable electric valves 4 of the make-alive type for controlling the flow of current through the connecting transformer 3. Each of the make-alive type valves 4 comprises a suitable container 5, preferably of metal, which can be evacuated, a vaporizable reconstructing cathode of suitable material, such as mercury, contained in the bottom of the container, a main anode 7 spaced from and insulated from the cathode 6, an anode grid 8 preferably of conducting material, such as graphite, in closely spaced relation to the main anode 7, and a make-alive electrode 9 in permanent contact with the vaporizable cathode 6. The make-alive electrode 9 is periodically supplied with energy to initiate a cathode spot for initiating a main current-carrying arc between the anode 7 and the cathode 6.

The current impulses to the make-alive electrode 9 are supplied by a suitable control trans-

former 10, the phase terminals 11 of which are connected through suitable impedances 12 and 13 to the make-alive electrode 9, and the flow of current to the make-alive electrode is controlled by a suitable auxiliary rectifier or firing tube 14, preferably of the grid-controlled type. In order to conserve energy in the control transformer 10, suitable energy-storing devices, such as capacitors 15, are connected in parallel with the phase windings 16 of the control transformer 10. The charging current of the capacitors 15 is controlled by suitable impedances 12, which may be either resistors or reactors, or a combination of both. Also, the discharging current characteristic of the capacitors 15 is controlled by means of a suitable impedance 13, preferably of considerable less ohmic value than the impedance 12 between the phase terminal 11 and the capacitor 15, so that the capacitor 15 is charged over a considerable interval of time, but the capacitor 15 is discharged in a much shorter interval of time to produce a peaked impulse for application to the make-alive electrode 9. Preferably, the control transformer 10 is connected in a phase relation advanced to the phase relation of the main transformer 3, so that the potential of the phase windings 16 of the control transformer 10 is at its peak value at the instant of starting the cathode spot in the make-alive type valve 4.

30. The firing tubes are controlled by a suitable firing transformer 20, the phase position of which may be controlled by any suitable means, such as the rotary phase shifter 21 interposed between the source of alternating-current 2 and the primary 22 of the firing transformer 20. Obviously, by shifting the phase relation, the firing instant can be changed at will with respect to the phase position of the main transformer 3.

In order to insure pick-up of the main current-carrying arc after the establishment of the cathode spot by the make-alive electrode 9, we have supplied an auxiliary source of excitation potential herein illustrated as an auxiliary transformer 25, although obviously any suitable source of potential can be utilized. This auxiliary potential is connected to the anode shield 8 so that it forms an exciting electrode adjacent to the anode 7, and brings the ionization into the vicinity of or in contact with the anode 7, thus insuring ready pick-up of the main current-carrying arc. Preferably, the phase relation of the exciting transformer 25 is substantially in phase with or leading that of the main transformer 3, so that the exciting current to the shield 8 terminates with the termination of the current-

carrying arc between the main anode 7 and cathode 6.

In the operation of the converter according to our invention, potential is applied to the control transformer 10 and to the exciting transformer 25 so that alternating current is applied to the anode shields 8, and the control transformer 10 charges the capacitors 15 in readiness for initiating operation. The firing transformer 20 then releases the firing tubes 14 so that the make-alive valves 4 are successively periodically activated for the transfer of current between the alternating-current circuit 1 and the direct-current circuit 2. Obviously, the amount of current transferred can be controlled by the phase shifter 21 in series with the firing transformer 20. The exciting transformer 25 supplies exciting current to the anode shields 8 which act as exciting electrodes, to ionize the arc space and insure ready pick-up of the main current-carrying arc in the make-alive type valves 4.

The modification according to Fig. 2 is substantially identical so far as the main current and igniting circuits are concerned, but the auxiliary transformer or exciting transformer 25 has been dispensed with, and a suitable mid-tap 30 provided in each of the phase windings 16 in the control transformer 10 for supplying exciting current to the anode shields 8 which act as exciting electrodes.

While for purposes of illustration we have shown and described specific embodiments of our invention, it will be apparent that changes and modifications can be made therein without departing from the true spirit of our invention or the scope of the appended claims.

We claim as our invention:

1. A control system for a vapor-electric valve of the make-alive type, said valve including a main anode and a cathode, a make-alive electrode in contact with the cathode, an anode shield substantially enclosing the anode, a con-

trol transformer for supplying control potential to the make-alive electrode, means for periodically applying current impulses from said control transformer to said make-alive electrode for initiating a cathode spot in said make-alive valve, an auxiliary source of exciting potential independent of the load, and means for impressing the exciting of said auxiliary source on said anode shield.

- 10 2. An electric current conversion system comprising a plurality of make-alive type valves, each valve including an anode, a cathode, a make-alive electrode in contact with the cathode, and an anode shield about the anode, a controlling transformer having a plurality of phase windings conforming in number to the make-alive electrodes to be excited, a firing tube connected in series between each of said phase windings and said make-alive electrodes, means for determining the conductivity of said firing tubes, an intermediate tap in each of said phase windings and connections for impressing the potential of said intermediate tap on said anode shield for ionizing the arc space between the anode and cathode.
- 15 3. A control system for a vapor-electric valve of the make-alive type comprising a valve having a pair of cooperating main electrodes, a make-alive electrode in contact with one of said main electrodes, a shield substantially enclosing the other main electrode, a control transformer, connections for impressing the potential of said control transformer across the make-alive electrode and the main electrode in contact therewith, means in said connections for controlling current flow to said make-alive electrode, an intermediate tap in said control transformer and circuit means for impressing the potential of said intermediate tap on said shield.
